UNITED STATES PATENT OFFICE.

HERBERT OSMOND CRIPPEN, OF NEW YORK, N. Y.

SPIKE.

1,074,409.

Specification of Letters Patent. Patented Sept. 30, 1913.

Application filed November 16, 1912. Serial No. 731,692.

To all whom it may concern:

Be it known that I, HERBERT O. CRIPPEN, a citizen of the United States, and a resident of the city of New York, borough of Manhattan, in the county and State of New York, have invented a new and Improved Spike, of which the following is a full, clear, and exact description.

This invention relates generally to spikes, and is particularly directed to improvements in the subject matter described in Letters Patent No. 963,280 issued to me July 5, 1910, and in a pending application, Serial No. 681,262 filed March 2, 1912.

15 The objects of this invention contemplate improvements in railroad spikes of the kind above identified, and more particularly the objects of the invention may be stated as follows: To position the fulcrum of the 20 toothed plates at the sides of the spike to one side of the longitudinal center thereof in order to provide for a greater relative movement of the plates, thereby tending to more effective securing of the spike within 25 the ties and also in order to prevent the locking plates, which are detachable, from being assembled on the spike except with the teeth or serrations of the plates pointing always in one direction; to provide an 30 improved form of tooth on the movable plates whereby the passage of the spike into the tie is facilitated, the teeth on the plates being staggered, thereby insuring greater holding power due to the fact that different 35 fibers of the wood are engaged by the several teeth; and, more specifically, to provide an improved form of mounting for each plate so that as the spike is being driven the plate will be held in operative 40 relation with the spike, being prevented from separation due to the reaction.

The particular structure and its modification herein illustrated and described set forth one manner of obtaining the above 45 purposes, it being clear, however, that various changes may be made in such structures without departing from the inventive idea disclosed.

Reference is to be had to the accompanying drawings forming a part of this specification, in which like characters of reference indicate corresponding parts in all the views, and in which—

Figure 1 is a side view of the spike, with 55 the plate carried thereby; Fig. 2 is a perspective view of the spike, with the plates

in the position they lie when driven into the tie, the staggered relation of the teeth being shown; Fig. 3 is a partial view of the spike, showing the structure adjacent the lower end for mounting the plate; Fig. 4 is a sectional view of the tie and a portion of the rail, showing the spike and the plate in operative relation thereto, the particular form of the teeth being exemplified; Fig. 5 is a sectional view on the line 5—5 of Fig. 1; while Fig. 6 is a perspective view of a modified manner of mounting the plate.

The spike comprises a body member 1 and plates 2 movably mounted on the opposite sides thereof; while the spike discloses two plates it is, of course, clear that one plate may be used with the identical body member, if so desired.

The body member is preferably of integral construction, having the driving end 3 enlarged to form a head, the driven end being tapered in order to form an entering wedge 4, the particular dimensions of the ends being of little consequence. On opposite sides of the body member, and adjacent the driven end, are curved pockets 5, the depths of which are equal to the thickness of the plates 2; referring particularly to Fig. 3 it will be noted that the pocket 5 is provided in what may be termed a shoulder 6 having converging end portions or surfaces 7^a—7^b, the former of which being longer than the latter.

Each plate 2 is substantially flat and of a length sufficient to reach from the pocket 5 to a point adjacent the head 3, one edge portion of the plate being provided with a number of teeth or spurs 8; as shown particularly in Fig. 2, in the event that the plates are held at opposite sides of the body member 1 the teeth on one plate will lie intermediate the teeth on the other plate, thereby providing a staggered relation. The upper end of each plate is provided with an offset portion 9 adapted for engagement with the edge of the lower flange 10 of the rail 11, so that as the spike is driven into the tie 12 the engagement of this said portion 9 of the plate will bring it into the position shown particularly in Fig. 4. The lower end of the plate is provided with an extension 13, substantially, although not essentially, circular, the extension lying adjacent the lower ends of the tapering side 105 portions 14^a—14^b of the plate; this extension is substantially of less extent than the

pocket 5, so that free movement of the plate 2 relatively to the body member 1 is permitted, it being noted, however, that the distance between the lower ends of the tapering edge portions 7^a—7^b of the shoulder 6 on the body member 1 is substantially less than the width of this extension, so that once the extension is positioned within the pocket it cannot be removed therefrom by an upward longitudinal movement of the plate, which movement is brought about when the spike is being driven into the tie.

The particular arrangement of the converging edge portions 7^a—7^b on the shoulder 6 insures the proper positioning of the plate 2 adjacent the side of the body member 1, so that the serrated edge of the plate will always bear the relation to the head of the body member as shown; as shown particularly in Fig. 1, one edge portion of the plate 14^a tapers similarly to the edge portion 7^a of the shoulder 6, so that the engagement between these tapering portions provides for the proper position of the plate adjacent the side of the body member when the spike is being driven; that is, the engagement of the material of the tie with the serrated edge of the plate is prevented from moving the plate due to such engagement. It will be noted that the center of gravity of the plate 2 is at such side of a vertical line passing through the pivotal center between the body member 1 of the spike and plate 2, as to maintain the edge 14^a of the plate against the shoulder 6 of the body member 1 when the spike is in upright position, as shown in Fig. 1. Apart, however, from this particular manner of mounting the lower end of the plate is the idea of providing the pocket, or the bearing point for the end of the plate in the pocket, to one side of the longitudinal center of the body member 1 so that when the plate 2 is moved to one side into the position shown in Figs. 2 or 4 a greater extent of the teeth or spurs 8 will engage the fibers of the material in the tie 12. Another reason for so positioning the pivotal point between the locking plate 2 and the spike is that the plate cannot be placed on the spike in any except the proper position with the teeth thereof pointing always in one direction or oppositely from the direction in which the head of the spike points. This departure from what is shown in the Letters Patent and the co-pending application hereinbefore referred to, sets forth a structure possessing marked advantages because of the greater degree of engagement between the fibers and the spurs. Various constructions may be availed of in order to bring about this eccentric mounting of the lower end of the plate apart from what is shown in Figs. 1 and 4, and in Fig. 6 one modification is shown. In this instance the pocket 5 is omitted, the shoulder 6' on the body member 1

being provided with downwardly extending and converging sides 7^c—7^d, the meeting edge 15 of the sides providing the pivotal support for the lower end of the plate 2; this structure in no wise differs from that shown in Figs. 1 and 4 as far as the results aimed at are concerned.

Referring particularly to Figs. 1 and 4 it will be noted that the form of tooth or spur is different from what is shown in the Letters Patent and co-pending application hereinbefore referred to, the particular form of the tooth permitting of certain desirable functions. The side edge 16^a of each tooth 8 is a compound curve, the curvature at the tip 16^b being convex, and the top edge of each tooth is concave and merges smoothly into the side edge of the tooth next above. The top and side edges of each tooth form a sharp hook-shaped point which bites deeply into the fiber of the tie when the locking plate is forced laterally, as in Fig. 4, it being noted particularly that this relation of the curved edge portions 16^a—16^b provides for slipping of the tooth across the fibers of the tie as the spike is being driven, in counter-distinction to tearing or rupturing of these fibers; this slippage, then, permits the easy entrance of the teeth into the wood, forcing the fibers thereof to one side so that after any tooth or spur has passed certain particular fibers they will tend to assume their former position in the path of the tooth, but above it, thereby insuring a firm positioning of the teeth within the wood.

Referring again to the manner of mounting the lower end of the plate 2 on the body portion 1, it will be noted that in Fig. 6 a shoulder 17 is provided beneath the head 3, which shoulder prevents upward movement of the plate relatively to the body member as the spike is being driven, the structure shown in Figs. 1 and 4, however, doing away with the necessity of such shoulder because of the locked relation of the extension 13 at the lower end of the plate in the pocket 5. As far as the engagement of the spurs in the tie is concerned either form of mounting means for the plate may be availed of, and spikes embodying these different features may be withdrawn with equal facility. In this connection it may be noted that the upper end of the plate 2 adjacent the toothed edge provides a portion 18 which, when the spike is in driven relation as shown in Fig. 4, permits the plate to be moved relatively to the body member by engagement of the crowbar with the said portion 18 as the ends of the bar are brought into engagement with the under side of the head. In withdrawing the spike the opposite movements of the parts are gone through, that is, as the head moves upwardly through a certain distance the plate 2 moves relatively to the body member 1, coming into the relation shown in Fig. 1,

with the teeth out of engagement with the fibers, the aforesaid upper portion 18 providing for such operation.

The spike described is of simple structure, 5 the plates being easily made and not presenting difficulty in the stamping operation, the spike as a whole tending to a structure which will more efficiently retain its position within the tie and prevent spreading of the 10 rail.

Having thus described my invention, what I claim as new and desire to secure by Letters Patent is:

1. A spike comprising a body member, 15 and a plate movably carried thereby and to one side thereof, the center of movement of the said plate being to one side of the longitudinal axis of the body member.

2. A spike made up of a body member, 20 and a plate in movable relation thereto, the side of the body member being provided with a shoulder forming a support, the end of the plate being provided with a portion engaging the said support and about which 25 the plate may be moved, the said point of support lying to one side of the central axis of the body member.

3. A spike comprising a body member, 30 and a plate movably carried thereby and to one side thereof, the side of the body member being provided with a pocket, the end of the plate being provided with an extension engaging in the pocket, the said pocket and extension normally lying to one side 35 of the longitudinal axis of the body member.

4. A spike comprising a body member, 40 and a plate movably associated therewith, one side of the spike being provided with a pocket, the end of the plate being provided with an extension engaging in the said pocket, the entrance to the pocket adjacent the side of the body member being of lesser dimension than the width of the said extension, whereby the extension is prevented 45 from withdrawal from the pocket by a longitudinal movement.

5. A spike comprising a body member, 50 and a plate movably associated therewith, one side of the body member being provided with a shoulder, the upper portion of which is provided with downwardly converging edge portions, and a pocket in the shoulder and below the said converging edge 55 portions, the plate being provided with an extension adjacent its lower end fitting in the said pocket, the extension being incapable of withdrawal from the pocket by a longitudinal movement of the plate.

6. A spike comprising a body member 60 provided adjacent its point with a shoulder, and a plate pivotally connected with the body adjacent the shoulder and having its center of gravity so positioned as to 65 maintain the plate in engagement with the

shoulder when the spike is upright, said plate having means adapted to be projected laterally from the spike as the latter is driven home.

7. A spike comprising a body member, a 70 shoulder thereon, and a plate pivoted on the body member adjacent the shoulder and arranged with its center of gravity so located as to maintain the plate in engagement with the shoulder, the edge of the plate at its free end normally projecting beyond the body member and the other edge of the plate being adapted to project beyond the body member when the first edge is moved inwardly as the spike is 80 driven home.

8. A spike comprising a body member, a shoulder adjacent the driven end, a pocket in the shoulder, the edge portions of the shoulder adjacent the pocket converging 85 downwardly, a serrated plate associated with the body member and provided with an extension entering the said pocket, one edge portion of the plate adjacent the extension tapering similarly to one edge portion of the shoulder adjacent the pocket, whereby the engagement of the said tapered portions will maintain the plate and the body member in driving relation.

9. A spike comprising a body member 95 adapted to be driven into a tie and a plate lying adjacent one side of the body member and serrated along the longitudinal edge, the point of pivotal relation of the body member and the plate being to one 100 side of the longitudinal central axis of the body member, and engaging portions on the body member and the plate, whereby the parts may be maintained in proper relation as the spike is being driven.

10. A spike comprising a body member and a detachable toothed locking plate carried by the body member and having a pivotal point of engagement therewith, the member and plate having coöperating parts 110 whereby the plate can be placed on the body in only one position.

11. A spike comprising a body member having adjacent its point a shoulder formed with oppositely-inclined surfaces and a 115 locking member pivoted at the shoulder and having edges coöperating with the said surfaces of the shoulder, whereby the locking plate can be mounted on the body member in only one position, said locking plate having means for engaging the fiber of the body into which the spike is driven.

12. A spike comprising a body member, a locking plate movably mounted on the side of the member, and teeth on the plate 125 each formed with a compound curved side and with an inwardly-curved upper edge merging smoothly into the concave portion of the side edge of an adjacent tooth.

13. The combination of a spike compris- 130

ing a body member, locking plates movably mounted on the sides of the body member and each having at one edge a plurality of teeth, one plate having more teeth than the other and in staggered relation thereto, and the plates having means whereby the latter are forced laterally as the spike is driven home.

14. The combination of a spike comprising a body member, and locking plates movably mounted on the sides of the body member and each having at one edge a plurality

of teeth, said plates being at their upper ends wider than the body member of the spike, whereby the said wider ends cause the plates to be moved laterally as the spike is driven home.

In testimony whereof I have signed my name to this specification in the presence of two subscribing witnesses.
